RUBBING MACHINE

Ottmar A. Kehle, Detroit, Mich., assignor to Sterling Products Company, Detroit, Mich., a corporation of California

Application November 7, 1934, Serial No. 751,838

6 Claims. (Cl. 51—170)

My invention relates to a new and useful improvement in a rubbing machine adapted for use in rubbing various surfaces, and from the description of the invention it will be noted that

5 the invention may also be used for abrading.

It is an object of the present invention to provide in a rubbing machine of this class a rubbing member associated with actuating mechanism so arranged and constructed that the rubbing member may be reciprocated while remaining in a single plane. It is another object of the present invention to provide in a rubbing machine of this class mechanism whereby the rubbing element may be reciprocated by means of a rotating shaft.

10 15 It is another object of the present invention to provide in a rubbing machine of this class a rubbing member associated with mechanism whereby the rubbing member may be reciprocated through the medium of an electric motor.

20 Another object of the invention is the provision of a rubbing machine of this class in which a rotating cam may be utilized to effect a reciprocation of the rubbing member.

25 Another object of the invention is the provision in a rubbing machine of this class of means for easily and quickly attaching a pad in position for supporting the rubbing medium.

30 Another object of the invention is the provision of means for mounting a supporting pad in such a manner that it may be reciprocated bodily and retained in a constant plane and maintained free from flexing.

35 Another object of the invention is the provision in a rubbing machine of this class of a supporting handle whereby the machine may be held free from shocks and vibrations.

40 Another object of the invention is the provision in a rubbing machine of a mechanism in which there is an actuating part adapted for reciprocating a supporting part so constructed and arranged that a pad supported thereon may be reciprocated through delivery of force to the supporting part, while at the same time the pad will be maintained free from twisting strains or force.

45 Other objects will appear hereinafter.

The invention will be best understood by a reference to the accompanying drawings which form a part of the specification and in which,

50 Fig. 1 is a central longitudinal vertical sectional view of the invention with a part broken away.

Fig. 2 is a sectional view taken on line 2—2 of Fig. 1.

Fig. 3 is a sectional view taken on line 3—3 of Fig. 1.

55 Fig. 4 is a fragmentary longitudinal vertical

sectional view of a modified form of the invention.

Fig. 5 is a view taken on line 5—5 of Fig. 4 and reduced in size.

Fig. 6 is a fragmentary longitudinal sectional view of a further modified form of the invention. 5

Fig. 7 is a view taken on line 7—7 of Fig. 6 slightly reduced.

Fig. 8 is a central longitudinal vertical sectional view of a further modified form of the invention.

Fig. 9 is a sectional view taken on line 9—9 of 10 Fig. 8.

Fig. 10 is a fragmentary side elevational view of a further modified form with parts broken away and parts shown in section.

Fig. 11 is a sectional view taken on line 11—11 15 of Fig. 10.

Fig. 12 is a side elevational view with parts broken away and parts shown in section of a further modified form.

Fig. 13 is a sectional view taken on line 13—13 20 of Fig. 12.

In the drawings I have shown several forms of rubbing pads, and in the forms shown in Figs. 1 to 6, inclusive, the pad in itself is of a well known type and is merely illustrated to show the adaptation of the other mechanism to a pad of this 25 class or type of construction.

In the form shown in Fig. 1, I provide a base 21, on which is suitably mounted a housing 22. Mounted on the housing 22 is a handle 23 which 30 projects outwardly at one end from a cross-head 24. The end of the handle and the cross-head are slotted at 25 and extending outwardly from opposite sides of the handle are the arms 26 and 27 which are adapted to embrace the housing and 35 clamp a layer 28 of rubber or other yieldable material thereon upon a threading of the nut 29 on to the bolt 30. This provides a convenient handle whereby the mechanism may be held in use, and due to the manner of mounting and the construction of the handle the vibrations of the machine transmitted to the hands of the operator are reduced to a minimum. 40

Projecting outwardly from one end of the housing 22 is a neck 31 threaded on which is the connecting fitting 32 in which is threaded the screw 33 having its inner end reduced and engaging in the peripheral groove 34 formed in the connecting shaft 37. This connecting shaft 37 is connected to a flexible shaft 36 which it is intended to rotate by means of an electric motor. A protective sleeve or sheathing 35 is mounted on the outer end of the fitting 32 and serves to enclose the flexible shaft 36. The inner end of the connecting shaft 37 is provided with a socket 37' in which 45 50 55

engages the reduced shaft 38 projecting outwardly from one end of the operating shaft 39 and journalled in the standard 40. A stub shaft or reduced extension 41 extends outwardly from the opposite end of the operating shaft 39 and is journalled in the standard 41.

Slidably mounted on the operating shaft 39 is a sleeve 42 which carries the screw 43. The upper end of the screw 43 is reduced to provide the reduced extension 44 and rotatably mounted on this reduced extension 44 is a roller 44. This roller 44 engages in the peripheral spirally directed groove 45 formed in the operating shaft 39. This groove, when the shaft 39 is being rotated, serves as a cam groove for effecting reciprocation of the sleeve 42 and the screw 43. This screw 43 is provided with the extension 46 which projects through the opening 47 formed in the upper side of the flexible supporting pad 48 which is preferably made from rubber. This pad 48 is mounted by means of the bolt 49 on the base 21. The bottom 50 of the pad is connected to the top 48 by means of the ribs or partitions 51. Mounted on the upper surface of the bottom 50 is a plate 52 having a guide sleeve 53, in which the extension of 43 slidably engages. Formed in the sides of the pad is a groove 54 in which a resilient locking member 55 may serve to retain the edges of a layer 56 of emery cloth or other suitable rubbing or abrading material. The layer 56 serves to cover the cushion layer 56' which is glued to the outer face of the bottom 50. This layer 56' is formed from a soft yieldable material.

In operation when the flexible shaft 36 is rotated the actuating shaft 39 will be rotated, and this will effect a reciprocation of the extension 46 so as to reciprocate the bottom 50. The end walls of the supporting pad are sufficiently flexible to permit this reciprocating movement. In the form shown in Fig. 4 I have provided a method of mounting the pad whereby the pad may be easily and quickly removed from the base 21 and replaced thereon. Mounted on the base 21 is a layer 57 formed preferably from spring metal. The opposite edges of the plate 57 are turned inwardly to provide the inwardly directed flanges 58 which were designed to interlock with the inwardly directed flanges 69 formed on the opposite ends of the plate 59 which is attached to the top 48 of the pad. Formed on one of the flanges 69 is the outwardly projecting tongue 61. These flanges are struck on an arc, as clearly appears on Fig. 5, and when it is desired to mount the pad in position the extension 46 of the screw 43 is engaged in the guide sleeve 53 while the pad extends angularly to the plate 21. The pad is then rotated into position, thus interlocking the flanges 58 and 69.

In Fig. 6 and Fig. 7, I have shown a slightly different form in which there is provided a retaining bead 62 at the opposite ends of the plate 21, and this bead 62 is adapted to interlock with the inwardly turned flanges 63 formed on the plate 64 which is attached to the top 48 of the pad. An outwardly projecting tongue 65 is formed on one end of the plate 64. As shown in Fig. 7 the pad is again mounted in position by a swinging movement referred to in the description relating to Fig. 4 and Fig. 5.

In the form of pad shown in Fig. 1 to Fig. 6, inclusive, when the reciprocating action is transmitted to the pad, the outer or rubbing surface of the pad will swing in an arc until it is flattened out through contact with the surface to be rubbed. In other words, this outer surface will curl inwardly at its ends. This results from forming the

pad integral with the supporting structure and from fastening the pad at its upper end. Consequently, when the outer or rubbing surface of the pad engages the face of the body to be rubbed, unequal pressure will be transmitted to the surface at different points.

This is an undesirable feature of rubbing machines of this kind and may be avoided in the two ways which I have illustrated herein. In the forms shown in Fig. 10 and Fig. 12 a bodily reciprocation of the pad is effected without necessarily effecting a distortion of the supporting means. In the forms shown in Fig. 8, the pad is reciprocated while remaining in a single plane and the pad is free from any strains tending to twist it, bend it, or swing it in an arc. In this form I provide as a part of the actuating mechanism, loops 66 which are formed from resilient material and which are connected to the plate 21 by means of the clamping plate 67 and the bolts 68. The lower ends of these loops are connected to the plate 71 by the clamping plate 69 and the bolts 70. The plate 71 is provided with the recess or groove 72 in which may engage the spring band 73 which serves to clamp the covering 56 over the cushion 56' which is glued to or otherwise secured to the under-surface of the plate 71. The guide sleeve 53 is carried by the plate 69, and the screw extension 46 projects into the sleeve 53. The screw extension 46 is provided with a head 246 which engages in the guide sleeve 53 and is prevented from withdrawal therefrom by the inwardly turned flange 253 on the end of the guide sleeve 53. As clearly shown in Fig. 9, the screw head 246 in normal position is spaced from the flange 253. When the reciprocating action takes place, the loops 66 will be distorted out of their normal shape, but the plate 71 will move in a single plane. This plate 71 is flexible as is likewise the cushion 56', so that while these parts move in a plane and are free from bending or distorting strains, they will accommodate themselves to depressions and protuberances on the surfaces rubbed. Thus I provide a supporting member which may be distorted, but which, in its distortion, will not effect a distortion of the rubbing pad itself.

In the form shown in Fig. 10 I have again illustrated a slightly different type of pad mounting as well as a different type of pad. In this form I provide a rectangular preferably flexible band 14 secured to the top 75 of which is a metal plate 16. Through this plate 16 the screw 77 projects. This screw threads into the sleeve 42 and the sleeve 42 embraces the operating shaft 39 as shown in Fig. 1. Threaded on the screw 77 is a nut 18 which serves to clamp the washer 19 against the plate 16. The cushion pad 56' is retained in position by the layer 56 of emery cloth, sand paper, or the like, which is retained in position by the spring retaining loop or band 80. The construction is such that as the screw 77 is reciprocated the entire structure 74 reciprocates bodily.

In the form shown in Fig. 12 I have shown a substantially similar type of mounting as that shown in Fig. 10, excepting that there is rotatably mounted rollers 81 which are adapted to engage the plate 16. In this form the plate 16 is provided with the upwardly turned flanges 82 to which may be attached a dust shield 83.

It is believed obvious from the various forms illustrated that a mechanism is thus provided which will accomplish the object sought.

While I have illustrated and described the preferred forms of construction I do not wish to limit myself to the precise details of structure 75

shown, but desire to avail myself of such variations and modifications as come within the scope of the appended claims.

Having thus described my invention what I claim as new and desire to secure by Letters Patent is:

1. In a rubbing machine of the class described an actuating mechanism; a housing for enclosing said mechanism; a detachable handle mounted 10 on said housing; and a yieldable layer of shock absorbing material between said handle and said housing.
2. In a rubbing machine of the class described an actuating mechanism; a housing for enclosing said mechanism; a detachable handle mounted 15 on said housing; a yieldable layer of shock absorbing material between said handle and said housing; means for mounting said handle on said housing in clamping relation thereto.
3. In a rubbing machine of the class described a supporting structure; a retaining plate mounted 20 on said structure having the opposite ends struck on an arc; an inwardly projecting flange on the opposite ends of said plate; a rubbing pad; a retaining plate mounted on said pad; inwardly 25 projecting arcuate flanges on said last mentioned plate engageable with the flanges on the first mentioned plate for mounting said pad on said structure.
4. In a rubbing machine of the class described a supporting structure; a retaining plate mounted 30 on said structure having the opposite ends struck on an arc; an inwardly projecting flange on the opposite ends of said plate; a rubbing pad; a retaining plate mounted on said pad; inwardly 35 projecting arcuate flanges on said last mentioned plate engageable with the flanges on the first

mentioned plate for mounting said pad on said structure; and means on one of said plates for manually effecting relative rotation of said plates for disengaging the same from each other.

5. In a rubbing machine of the class described, 5 a rubbing pad; a supporting structure; a plurality of flat resilient strips doubled upon themselves to provide loops; means for connecting said loops on said supporting structure with the outer face of said loops engaging said supporting structure; means for connecting said rubbing pad to said loops diametrically opposite the connection of said loops to said supporting structure and in engagement with the outer face thereof, said loops retaining said pad connected 10 to and in spaced relation to said supporting structure, the curvature of said loops extending outwardly toward opposite ends of said pad.

6. In a rubbing machine of the class described, 20 a rubbing pad; a supporting structure; a plurality of flat resilient strips doubled upon themselves to provide loops; means for connecting said loops on said supporting structure with the outer face of said loops engaging said supporting structure; means for connecting said rubbing 25 pad to said loops diametrically opposite the connection of said loops to said supporting structure and in engagement with the outer face thereof, said loops retaining said pad connected to and in spaced relation to said supporting structure, the 30 curvature of said loops extending outwardly toward opposite ends of said pad; and an actuating mechanism mounted on said supporting structure for reciprocating said pad relatively to said supporting structure longitudinally of said 35 loops.

OTTMAR A. KEHLE.
